REISSUED

DOOR CONTROL MECHANISM

John M. Hunter, Cumberland, Ohio

Application June 22, 1934, Serial No. 731,935

9 Claims. (CL. 20—16)

This invention relates to door control mechanism for swinging doors of garages and the like operating to cause a pair of doors to open and close in unison.

5 The principal object of this invention is to provide an improved door control which will permit the doors to simultaneously swing through practically one hundred eighty degrees from their closed positions to full open positions, while 10 retaining at all positions a proper controlling leverage so that moving one door in either direction will correspondingly move the other door.

Another object of this invention is to arrange 15 the connecting linkage in such a manner as to obtain a more direct pull or push of a link actuated by one door on the corresponding link of the other door at the times in the opening and closing cycles of the doors of the maximum 20 forces and resistances, so as to reduce to a minimum the cramping or binding action of the links on each other and on the guiding means. Other objects are to couple the doors so that the force 25 of a cross wind tending to close one of the doors will be counteracted by the opening force exerted on the other door; to provide a simple, cheap and easily installed construction that will operate efficiently and that requires little or no 30 attention to maintain it in proper operating conditions; and to arrange the parts so that a single standardized construction may be adapted to fit the great majority of swinging door garage 35 constructions. Other objects will be apparent from the following detailed description of the preferred embodiment of the invention.

In the accompanying drawings:

Figure 1 is a top plan view of the doors and connecting mechanism as applied to a conventional garage, the roof of the garage being removed, and the doors being shown closed in full lines and partially opened in dotted lines.

Figure 2 is a similar view showing the doors fully opened.

Figure 3 is a section taken on the line 3—3 of 45 Figure 2.

Figure 4 is a view taken on the line 4—4 of Figure 1.

Figure 5 is a detail view taken on the line 5—5 of Figure 2.

50 Figure 6 is a top plan view of the structure shown in Figure 5.

Referring to the drawings, the garage doors 5 and 6 are hinged at 7 and 8, respectively, to the opposite sides of the front wall 9 of the 55 garage. A header or cross frame member is positioned ordinarily above the door opening and behind the front wall 9, such a header being indicated at 10. In a single garage, as illustrated, the side walls are normally positioned but 60 a short distance laterally from the edges of the

door opening, such side walls being shown at 11 and 12, and the frame is provided with a cross member 13 parallel to, and in the same plane as, the header 10. In the great majority of single garages this cross member 13 is spaced 5 rearwardly from the doors a distance substantially equal to the width of the door opening and the other elements of the construction, with minor variations of proportions and dimensions, are arranged substantially as illustrated, and the 10 present invention is designed to be constructed in one form capable of being installed, with minor adjustments during the installation, in any garage of this type. It will be understood, however, that in its broader aspects the present 15 invention is not limited to any specific type of garage construction, but is adaptable, with suitable mechanical variations, to any swinging door arrangement.

In the embodiment illustrated, a suitable guide 20 member 14, which may be a tube or the like, has one end secured to the header 10 centrally of the door opening, and its opposite end secured in any suitable way to the cross member 13, or in the absence of such a cross member, to a 25 supporting bracket or the like. A short tubular member 15 having oppositely disposed apertured ears 15' slidably fits over the guiding tube 14. A pair of intermediate links 16 are pivotally mounted on the side walls 11 and 12 of the 30 garage in any convenient way, as by having their ends turned downwardly, as shown at 17, and fitting in vertical sockets 18 formed in plates 19 secured to the side walls.

The opposite end of each of the links 16 is 35 formed to pivotally connect with two other links. As illustrated, the free end of each link 16 is turned upwardly and pivotally fits in a socket 20 formed in a saddle 21 which is formed with a U-shaped portion straddling the link 16 and is 40 further provided with oppositely projecting apertured ears 22. A pair of links 23 connect the free ends of the links 16 with the tubular sliding member 15. To facilitate the construction and installation of the device, each link 23 has its ends 45 turned downwardly so that one end may be dropped into the aperture in one of the ears 15', and the other end may be dropped into the aperture in the adjacent ear 22.

A link 24 pivotally connects the free end of 50 each of the links 16 with the adjacent door. Preferably, each link 24 is also formed with down turned ends, one of which drops into the aperture in the other of the ears 22, and the other of which drops into an aperture in a bracket 25 secured to 55 the adjacent door at about its center. Each bracket 25 may be conveniently made from a strip of angle iron with one leg secured to the door and the other disposed horizontally and formed with a series of apertures to permit ad- 60

justment of the point of connection of the links 24 with the doors.

With the device installed and assuming the doors are in closed position as illustrated in dotted lines in Figure 1, it is evident that a pull upon either one of the doors will cause it to swing open. The link 24 connected to this door will pull and correspondingly swing the connected link 16, which in turn pulls the link 23 and slides 10 the tubular sliding member 15 forwardly, causing exactly similar and simultaneous movement of the remainder of the linkage and the other door. Likewise, the two doors are positively connected to move simultaneously in closing, it being necessary to manually manipulate but one of the doors to effect either opening or closing of both doors.

It will also be apparent that the connection of the doors with the intermediate links 16 through 20 the links 24 permits the doors to be swung through almost one hundred eighty degrees from their closed positions, the free ends of the links 16 being pulled out through the door opening during this action as illustrated in Figure 2 to 25 prevent the links 24 from fouling on the inner edges of the doors. This construction also acts to straighten the pull or push of the links 23 on the sliding member 15, since the angular relation of these links is at all times less than the 30 angle formed by lines extending from the points of connection of the links 24 with the doors to the ears 15'. In this way any tendency of the parts to cramp or bind is greatly reduced or eliminated and consequently the parts can be 35 made with greater tolerances and the life of the device is increased and the friction and wear greatly decreased. These advantages are present as well in connection with doors that need to be opened through but ninety degrees as with doors 40 which it is necessary or desirable to be able to open through one hundred eighty degrees. It will also be apparent that when the doors are opened a cross wind tending to blow one of the 45 doors shut will be counteracted by force of the wind striking the other door and tending to blow it open.

While a specific embodiment of the invention has been illustrated and described, it is to be understood that many modifications and rearrangements of the parts may be resorted to without departing from the scope and spirit of the invention as defined in the following claims.

I claim:

1. In combination, a pair of oppositely swinging doors, a swinging member associated with each door and connected therewith to swing in the same direction as, but at a different rate than, the door to which it is connected, and means coupling said swinging members to cause the same to swing simultaneously and in opposite directions.

2. In combination with a building structure having a pair of oppositely swinging doors, a pair of oppositely swinging members pivotally mounted on the side walls of said building structure, hinges connecting each of said doors to the building structure, means connecting each of said members to one of said doors, and means connecting said swinging members together for simultaneous movement.

3. In combination with a building structure having a pair of oppositely swinging doors, a pair

of oppositely swinging members pivotally mounted on said building structure, means connecting each of said members to one of said doors to swing therewith, a pair of articulated links one link being connected to each of said swinging members, and means for guiding said links to cause said swinging members to move in unison. 5

4. In combination with a building structure having a pair of oppositely swinging doors, a pair of oppositely swinging members pivotally mounted on said building structure, a link connecting each of said members to one of said doors to swing therewith, a pair of articulated links, one link being connected to each of said swinging members, and means for guiding said links to cause 10 15 said swinging members to move in unison.

5. In combination with a building structure having a pair of oppositely swinging pivotal doors, a pair of oppositely swinging members pivotally mounted on said building structure, a link connecting each of said members to one of said doors with a shorter distance between its connection to the door and the pivot thereof than 20 between its connection to said member and its pivot, and means connecting said swinging members to cause the same to move in unison. 25

6. In combination with a building structure having a pair of oppositely swinging doors, a pair of oppositely swinging members pivotally mounted on said building structure, a link connecting each of said members to one of said doors to swing therewith, each of said links being pivoted to one of said members at one end and pivoted to one of said doors at the other 30 35 end, and means connecting said swinging members to cause the same to move in unison.

7. In combination with a building structure having a pair of oppositely swinging pivoted doors, a pair of oppositely swinging members pivotally mounted on said building structure, a link connecting each of said members to one of said doors with a shorter distance between its connection to the door and the pivot thereof than between its connection to said member and the pivot thereof, a pair of articulated links, one link 40 45 being connected to each of said swinging members, and means for guiding said links to cause said swinging members to move in unison.

8. In combination with a building structure having a pair of oppositely swinging doors, a pair of oppositely swinging members pivotally mounted on said building structure, a link connecting each of said members to one of said doors to swing therewith, a guide rod fixed to said building structure and disposed perpendicular to said doors when closed, a connector slidably mounted on said guide rod and a pair of links pivoted to said connector, each of said links being pivoted to one of said members. 50 55

9. A device for causing a pair of oppositely swinging doors to swing in unison comprising a pair of jointed members pivotally connected together at one end, the free end of one of said jointed members being adapted to be connected to one of said doors and the free end of the other 60 65 of said jointed members being adapted to be connected to the other of said doors, and means adapted to be secured to a building structure to guide the joints of said jointed members through predetermined paths during swinging movement 70 75 of said doors.

JOHN M. HUNTER.
